ATTACHMENT FOR WINDOWS OR THE
LIKE

Elias Kaplan, Hoboken, N. J., assignor to Elias Kaplan, Inc., Hoboken, N. J., a corporation of New Jersey

Application July 20, 1934, Serial No. 736,149

3 Claims. (Cl. 156—14)

This invention relates to attachments for windows or doors and more particularly to screens or the like and to means for the attachment thereof in position of use.

5 Mosquito screens for windows as hitherto used are provided with wooden or other rigid frames which generally are made to removably fit in the guide grooves of the window sash or to be otherwise fixed to the window frames. Such construction has many disadvantages. First, the attachment and detachment of the screens are more or less difficult or tedious work and generally require skilled help. Another drawback is that when half screens are used and they engage the groove 10 of the window sash, the latter cannot be closed except on the removal of the screen.

If the screen is of the extendible type, in which case it is steadied in position by the window sash resting thereon, there is the disadvantage that 20 on lifting the sash the screen is liable to fall out.

A further disadvantage is that such screens of the hitherto used construction, having rigid frames, cannot be conveniently stored and shipped and that they are liable to be damaged easily.

25 The main object of my invention is to obviate said disadvantages. This I accomplish by providing a construction which consists of supports adapted to be permanently fixed to the window frame on the inside of the window, and of a screen which can be quickly and easily attached to and detached from said supports and which, when in position of use, will not interfere with the movement of the window sash. The screen per se is preferably made with flexible borders at 30 least along two opposite edges so that the screen may be conveniently rolled up either for storing or shipping purposes.

35 My invention also consists in certain details of construction whereby the manufacture will be greatly simplified and the cost of production minimized.

To make my invention more clear the same is 40 illustrated in the accompanying drawing in which similar characters denote corresponding parts and in which,

Fig. 1 is a front elevation of a part of a window and of my screen attachment, the screen having a flexible marginal border all around its four edges;

Fig. 2 is a vertical section on line 2—2 of Fig. 1 45 seen in the direction of the arrows;

Fig. 3 is an enlarged similar section of the attachment.

Fig. 4 is a front elevation of a detail of said attachment.

50 Fig. 5 is a sectional elevation of the screen at-

achment showing modified means for fastening the lateral supports to the window frame.

Figs. 6 and 7 are elevations of different modifications of the cross members holding the screen.

Fig. 8 is a cross section on line 8—8 of Fig. 7. 5

Fig. 9 is an elevation of a screen with flexible borders at its sides and rigid or reinforced borders at its upper and lower ends.

Fig. 10 is a cross section on line 10—10 of Fig. 9.

Fig. 11 is another modification of means for the 10 fastening of the screen to the cross members.

Fig. 12 is a section on line 12—12 of Fig. 11.

Fig. 13 is an elevation of a ventilator screen provided with means for its attachment to the lateral support and, 15

Fig. 14 is a section on line 14—14 of Fig. 13.

Referring now to the drawing more in detail, *a* denotes the frame of a window and *b* one of the vertically slidable sashes thereof. Adapted to be permanently fixed on the inside of the 20 window to the sides of said frame *a* to extend vertically are a pair of rigid members *10* which in the present embodiment of my invention are made in form of angle bars (Figs. 1, 2 and 4). These bars may be fixed to the window frame 25 by screws *11* as shown in Figs. 1 and 4, or by headed pins fixed in the frame and adapted to slidably engage keyhole shaped slots *12* (Fig. 5) provided in said bars. Each bar carries a longitudinal row of suitable fasteners, such as press 30 buttons *13* and additionally at each end a headed pin *13a* or the like. Adapted to removably engage said pins *13a* are a pair of cross members *14* carrying rows of fasteners *13* same as those of members *10* and which too may be in form of 35 angle bars. These cross bars are each formed at their ends with recesses or notches *14a* to slip over said pins *13a* and be securely held in position thereon as shown in Fig. 4.

The screen *15* according to the present embodiment of my invention, which may be a wire netting of a substantially rectangular shape, is provided around its four edges with flexible borders *16*. These borders *16* may be made of cloth or the like and secured to the wire netting 45 by sewing or otherwise. Provided on said borders are longitudinal rows of fasteners *17* which are the counterpart of the fasteners *13*, i. e. the female or male members of press buttons when using this type of fastener. Said fasteners 50 are distributed on the borders *16* so as to be in range with the fasteners *13* on the side members *10* and cross members *14* so as to enable the quick and convenient attachment and detachment of said screen. The side members *10* and cross 55

members 14 are so positioned relative to the sash b that the vertical movement of the latter in its guide groove a' of the window frame will not be obstructed and the window may be completely closed when desired. Suitably fixed to the upper cross bar 14 may be a flexible piece 18 of cloth, felt or other suitable material which may serve as weather strip or the like to more or less tightly close the interstice between the movable sash and the upper cross bar 14. This strip may be especially required when the sash has a projecting handle or grip, in which case the space between the sash and the cross bar will have to be larger than a mesh in the screen.

15 In accordance with the construction shown in Figs. 1 to 5 the bars 10 and 14 are made of standard size to fit a particular size of window and the screen, by reason of its flexible borders around its four edges can be rolled up from any of its edges to be convenient for storing or shipping.

20 The cross members and side members, instead of being of standard size may be made extendible in length to fit various sizes of windows. Said members may, to this end, be each composed of two longitudinally recessed sections adjustably joined to one another by pins 20, each section being provided with a series of fasteners 13 similar to those on cross bar 10 for the attachment 30 of the screen.

35 Instead of recessed sections extension pieces 21 may be used so that while using a member of standard size the latter, when found too short for a particular window, may be lengthened by the addition of said extension piece 21. Such extension pieces may also be made in different standard sizes. To facilitate the attachment of 40 said extension piece the latter, which may also be in form of an angle bar, may have at one end longitudinal recesses 21a, one in each side thereof, to removably engage headed pins 22 provided on the sides of the corresponding end of the member 23 as shown in Figs. 7 and 8.

45 In the modification shown in Figs. 9 and 10 the upper and lower edges of the flexible borders of the screen 15a are formed to pockets 24 to receive reinforcing ribs 25. These ribs will eliminate the necessity of using the cross bars heretofore described, while permitting the screen 50 to be rolled up from the sides when not in use. When using a screen with flexible borders all

around, the upper and lower borders may be fastened to cross bars 26 by clamping bars 27 as shown in Fig. 12.

5 The provision of permanently fixed lateral supports 10 on the window frame with rows of fasteners 13 thereon makes it possible to utilize said supports for the interchangeable attachment of ventilator screens and wire screens. Thus, for instance, ventilators in form of longitudinally recessed plates 28 with air deflectors 28a may be provided at their lateral edges with rows of fasteners 29 similar to the fasteners 17 to be counterparts of the fasteners 13, so that when desired the screen 15 may be removed and replaced by the ventilator 28.

15 It is clear that various changes may be made in the construction of my invention without departing from the principle thereof. I therefore do not wish to restrict myself to the details described and shown.

20 What I claim is:

1. In an attachment longitudinally extendible means for supporting a ventilating or similar device arranged on the inside of a window and secured to the window frame and means for removably fastening said device to said supporting means, said supporting means being longitudinally extendible to fit different sizes of windows.

2. In an attachment for windows, the combination of lateral vertical members of rigid material adapted to be fixed to the sides of the window frame on the inside of the window and each having a plurality of fasteners and a ventilating device having a plurality of corresponding fasteners at each of its lateral edges adapted to cooperate with said first named fasteners for the removable attachment of said device to said vertical members.

3. In an attachment for windows, the combination of lateral vertical members of rigid material adapted to be fixed to the window frame on the inside of the window, upper and lower cross members of rigid material removably engaging said vertical members, said vertical members and cross members each having a plurality of fasteners thereon and a screen having at each edge a plurality of fasteners adapted to cooperate with said first named fasteners for the attachment of said screen to said vertical and cross members.

50 ELIAS KAPLAN.
